UNITED STATES PATENT OFFICE.

CHARLES E. BLAIR, OF SOMERVILLE, MASSACHUSETTS, ASSIGNOR TO AMERICAN
WARP-DRAWING MACHINE COMPANY, A CORPORATION OF MAINE.

WARP-DRAWING-IN MACHINE.

1,153,855.

Specification of Letters Patent. Patented Sept. 14, 1915.

Application filed December 23, 1903. Serial No. 186,301.

To all whom it may concern:

Be it known that I, CHARLES E. BLAIR, of Somerville, in the county of Middlesex and State of Massachusetts, have invented certain new and useful Improvements in Warp-Drawing-In Machines, of which the following is a specification.

This invention has for its object the provision of means in consequence of which the drop-wires or the metallic heddles of a loom may be threaded upon the warp.

It has been heretofore proposed to provide a machine for automatically drawing the warp into the flexible heddles formed of cords or the like, in which the eye of the heddle was open and in position to receive the drawing-in needle. Such mechanism, however, is inapplicable for drawing the warp into flat metallic heddles or drop-wires, owing to the fact that such drop wires or heddles are arranged in their supports with their flat faces substantially parallel to the line of direction of the warp-threads. In drawing the warp into such metallic heddles or drop wires it is necessary that the drop wire or heddle should be presented with its face at an angle to the line of movement of the drawing-in needle or to the warp-thread, so that said thread may be passed through the eye thereof.

Consequently, one feature of the present invention consists of means for automatically presenting the drop-wires or heddles successively in position for the drawing-in of the warp-thread. This drawing-in operation may be accomplished by an operator with the aid of the common implement which is manually used, or it may be accomplished by an automatically-operated needle, as set forth in the patent to Field, No. 600,670, dated March 15, 1898.

In the embodiment of the invention which is illustrated upon the accompanying drawings, the drop wires or heddles are removed from their supports in the loom, and are placed in a magazine from which they are caused to be presented in succession in a predetermined position for the drawing-in of the warp.

Reference is to be had to the accompanying drawings, forming a part of this specification, in which,—

Figure 1 represents an end elevation of a

drawing-in machine embodying my improvements. Fig. 1^a represents the pawl 55 and ratchet mechanism for imparting power to the feeding mechanism. Fig. 2 represents a front elevation of the machine. Fig. 3 represents a plan view, parts being shown in section on line 3—3 of Fig. 2. Fig. 4 represents a section on line 4—4 of Fig. 3. Fig. 4^a represents a detail view of the divided nut hereinafter referred to. Fig. 5 represents a section on line 5—5 of Fig. 3. Fig. 5^a represents a perspective view of the divided nut. Fig. 6 represents a plan view of the wire magazine and a part of the drop-wire feeding mechanism. Fig. 7 represents a section on line 7—7 of Fig. 6, showing the drop wires in position and the method of feeding the same. Fig. 8 represents a section on line 8—8 of Fig. 6. Fig. 9 represents a perspective view of the magazine and a portion of the feeding mechanism. Fig. 10 represents a perspective view of the drop wire supporting and feeding mechanism represented in Fig. 9. Fig. 11 represents a perspective view of the receptacle in which the drop-wires are deposited after having the warp-threads drawn therethrough. Fig. 12 represents an enlarged perspective view of the upper portion of two of the drop-wires shown in Fig. 11 and in the same relative position with relation to each other. Fig. 13 represents an enlarged section on line 13—13 of Fig. 11, (looking downwardly,) the drop wires being shown as separated for the sake of clearness. Fig. 14 represents the drop wires in position to be placed in the magazine after the web of warp has been exhausted. Fig. 15 represents a section on line 15—15 of Fig. 14. Fig. 16 represents a section on line 16—16 of Fig. 4. Fig. 17 represents a section on line 17—17 of Fig. 16. Fig. 18 represents a section on line 18—18 of Fig. 16. Figs. 19 to 24, inclusive, illustrate a novel form of drop-wire which is particularly adapted for employment in conjunction with the drawing-in machine hereinbefore referred to, Fig. 19 illustrating a pair of such drop-wires. Fig. 25 illustrates another form of drop-wire which may be employed for the same purpose. Fig. 26 represents in perspective view some drop-wires, one or more heddles, and a warp-thread which is being passed

through one of the drop-wires and one of the heddles.

On the drawings is illustrated only that portion of the invention which includes the mechanism for presenting the drop-wires or heddles in position for the drawing-in of the warp-threads, and it includes a magazine or receptacle for the heddles or drop-wires, means for feeding them from the magazine, and a holder for the drop-wire or heddle by which the latter is maintained in position for the reception of the warp-thread. Where the warp-threads are drawn one at a time through the heddles or drop-wires, the magazine and holder may be mounted upon a carriage and advanced with a step-by-step movement relatively to the warp-beam or to the device which holds the warp-thread. For convenience, the drop-wires or heddles are laid one across the other in a pile, each pair of heddles forming as it were a St. Andrew's cross. The detents are arranged under the ends of the heddles and are so actuated that the heddles are dropped singly to the holder.

The machine illustrated in the drawings is adapted to act upon independent detached heddles. These are herein represented as flat metallic heddles of the kind usually formed out of thin resilient sheet metal and employed in the loom as drop heddles or drop wires. The invention, however, contemplates independent detached heddles of other forms and construction whether used as heddles or drop wires and also similar loom elements, the term "hebble" as well as the term "drop wire" being used in a generic sense to include both classes of devices.

In the drawings,—*a* represents the supporting frame which is provided with bearings *a*² in which is journaled the warp-beam *a*² having the warp *a*³ thereon.

*a*⁴ *a*⁴ represent horizontal guide-rods secured at each end to the frame, and upon which is mounted a carriage *a*⁵, which is adapted to be moved step-by-step lengthwise of the machine to distribute the drop wires at proper intervals, as will be hereinafter described.

Upon the carriage *a*⁵ is detachably mounted the magazine or receptacle *b* which contains the drop wires *b*¹. Said magazine is best shown in Figs. 3, 5 and 9, and consists of a plate *b*² detachably secured to the carriage by bolts *b*³ *b*³. To the plate *b*² is secured vertical rods or guides *b*⁴ by which the drop wires are held in crossed relation as shown. The upper ends of the rods *b*⁴ are secured to a removable cap *b*⁵ by nuts *b*⁶, said cap having a central depending guide-rod *b*⁷ passed through the eyes *b*⁸ in the drop wires, the arrangement being such that the rod *b*⁷, in conjunction with the rods *b*⁴, is enabled to hold the drop wires in the proper

position to be fed therefrom. The plate *b*² *b*⁵ is provided with diagonal slots or openings *c* (see Figs. 3, 6 and 7) which register with complementary openings in the carriage, so that the drop wires have free passage therethrough when permitted to drop one at a time by the feeding mechanism.

Upon the carriage is mounted the mechanism for feeding the drop wires, which includes crank-shafts *d* *d*¹ journaled in bearings *d*² *d*² *d*³ *d*³, secured to the carriage. Said crank-shafts are provided with crank-disks *d*⁴ having crank-pins *d*⁵ to which are journaled connecting rods *d*⁶, the lower ends of which are connected to the outer ends of arms *d*⁷ formed on short shafts *d*⁸ journaled in bearings *d*¹¹ upon the carriage. The shafts *d*⁸ have formed thereon on secured thereto blades or detents *d*⁹ *d*⁹ *d*¹⁰ *d*¹⁰, which act as supports for the drop-wires alternately and are so arranged through their connections with the crank-disks that but two of the detents are operated to support the drop wires in the magazine at the same time, as best shown in Figs. 9 and 10. It will

be seen that by reference to the last-mentioned figures that the diagonally-opposite detents *d*⁹ *d*⁹ act in unison to support the drop wires, while the detents *d*¹⁰ *d*¹⁰ act in unison to release the drop wire at the bottom of the pile, so that at each movement of the detents, their position is reversed, the detents *d*¹⁰ *d*¹⁰ assuming the supporting position, and the detents *d*⁹ *d*⁹ assuming the releasing position. The alternate releasing of the drop wires is effected by placing each drop wire in the magazine at an angle to the one below it, so that the bottom drop wire always rests upon one pair of detents and supports the pile above it, and as the detents are alternately swung downward, the drop wires are released one at a time.

The crank-shafts *d* *d*¹ which operate the detents are provided with bevel gears *e* *e* meshing with bevel gears *e*¹ *e*¹ on a shaft *e*². One of the crank-shafts *d*¹ is provided with an extension *e*³ on which is mounted a pinion *e*⁴ meshing with a pinion *e*⁵ mounted on a shaft *e*⁶ journaled in bearings on the frame *a*. On one end of the shaft *e*⁶ is mounted a pinion *e*⁷ meshing with a pinion *e*⁸ mounted on a shaft *e*⁹ journaled in bearings on the frame *a*.

The shaft *e*⁹ is rotated step-by-step by means of a ratchet *m* mounted on the outer end thereof, said ratchet being engaged by a spring-pawl *f* on the inner side of an arm *f*¹, as shown in Fig. 1^a. The arm *f*¹ is loosely mounted at its upper end on the end of the shaft *e*⁹, its lower or free end having a connecting rod *f*² suitably attached thereto, the other end of which engages a disk *f*³ mounted on a stud *f*⁴ secured to the frame, said disk being provided with a wrist-pin *f*²⁵ to which said outer end is attached. An arm

f^5 is secured to the disk to the outer end of which is attached a rod f^6 . The lower end of the rod f^6 engages the free end of a treadle lever f^7 , so that each time the treadle 5 is depressed one pair of detents is depressed to release a drop wire, and the other pair is elevated to support the remainder of the drop wires in the magazine.

The carriage is moved upon the guides a^4 by a screw f^8 , supported on the frame a and the outer end of which is provided with a ratchet f^9 (Figs. 1 and 3). Said ratchet is engaged by the free end of a pawl g , the other end of which is attached to the disk f^3 and adapted to be operated thereby, by means of the treadle already described. By reason of the construction as thus described, the depression of the treadle causes the intermittent advance of the carriage 20 relatively to the warp-beam and the actuation of the drop wire-feeding mechanism. The screw f^8 is in operative engagement with a divided nut g^1 secured to a lug g formed on the under side of the carriage 25 Figs. 4 and 4^a, and 5 and 5^a. The nut consists of two members g^3 g^4 hinged to a pintle g^5 secured to the lug g . A latch g^6 engages a lip g^{14} formed on the lower end of the member g^3 , which projects through a 30 slot g^{15} in the lower end of the member g^4 , and holds said members in engagement with the screw, so that when the carriage has been propelled by the screw to the limit of its travel, the nut may be opened from engagement with the screw, and the carriage moved 35 quickly back to its initial starting point.

The pinion e^6 is splined upon the shaft e^4 and the pinion e^4 is provided with a flange h which engages the sides of the pinion e^6 40 and moves the latter along therewith.

It is necessary that the drop-wires when released from the magazine should all be properly positioned when reaching the conduit h' , with the slotted end of each drop-wire uppermost. To this end, I have provided a rod w extending across the conduit h' , directly under the slotted portion of the drop-wires, so that when the latter are released from the magazine, they engage the 45 rod w , as shown in Figs. 5 and 7, whereby the slotted end of the drop-wire is retarded sufficiently to always permit the opposite end to enter the conduit z' .

After each drop wire is released by the 50 feeding mechanism, it is caught and held in position for the drawing-in of a warp-thread. One of the drop wires is shown in Figs. 5 and 7 in the act of being released from the magazine and being deposited in a 55 conduit h' , whence it passes to a holder z' attached to said conduit by an arm or bracket i . Said conduit is secured to the under side of the carriage, so as to move therewith; and at its upper end is complementary

with the openings e in the carriage and plate. The conduit tapers toward its bottom so that the drop wires, in passing therethrough, will register with and be deposited in the holder z' , from which they are passed into receptacles h^2 , extending lengthwise of 65 the machine and secured at each end to the frame thereof. Said receptacle has two compartments h^3 h^4 for the reception of the drop wires, being divided by a partition h^4 extending lengthwise of the receptacle. 70 Said partition has a central opening h^5 adapted to receive a suitable yielding material m' such as rubber hose, to make a yielding contact with one edge of the drop wires, as shown most clearly in Figs. 4, 80 5 and 11, and hold them securely in position.

The position of the drop wires as shown in the receptacle is at right angles to the position of the same when deposited in the 85 holder z' . By reference to Figs. 5, 16, 17 and 18, it will be seen that when the drop wire is in the holder its flat faces are longitudinal of the receptacle and parallel to the axis of the warp-beam, and it is in this 90 position when the warp-thread m^2 is drawn through the drop wire, after which it is turned at right angles and carried into the receptacle by the following means: The holder z' has two slots adapted to register 95 with the outlet of the conduit, so that when the drop wires are discharged from the said outlet they drop into the holder, through said slots, (Figs. 16 and 18) and are, after the warp-thread has been passed through 100 the drop wire, in condition to be turned at right angles in the receptacle.

Referring to Figs. 16 and 17, i^3 represents a tube secured at its upper end to the carriage and having a bend in its lower portion to connect with the holder z' . The tube is provided with a plunger i^4 , the upper end of which has a roll engaged by a cam i^5 on the shaft e^2 (Fig. 4). The portion of the tube immediately below the plunger is 110 provided with balls or other members i^6 , said balls being held in the position shown by a follower i^7 against the end of which a spring i^8 bears. The follower i^7 is provided with a stud i^9 passing therethrough, 115 and, also through slots k formed in the tube. On the outer ends of the stud i^9 is secured a T-shaped arm h^2 adapted to bear against one edge of the drop wire (see Fig. 16), so that when the cam i^5 is given a half 120 revolution, the plunger i^4 is depressed in the tube, the balls press forward the follower i^7 against the tension of the spring, and the T-shaped arm h^2 having contact with the drop-wire pushes said drop wire through 125 the slot in the holder z' , (the outer end of which is curved outwardly,) into the receptacle (Fig. 17). The end of each slot is

so shaped that as the drop-wire emerges from it, it is given a quarter turn on its longitudinal axis, and remains with its faces at right angles to its former position.

5 The drop wires, as they are fed to the holder, are required to be placed in the slots alternately. To effect this end I have placed in the conduit a deflector l which is secured to a shaft l' provided with an arm l^2 attached at its outer or free end to a rod l^3 . The upper end of said rod is provided with a roll l^4 adapted to bear against a cam l^5 on the shaft l^2 . The depression of the treadle by the operator causes the shaft l^2 to make 10 a partial rotation of the cam, which causes the deflector to assume the position shown in dotted lines in Fig. 1, and the next partial rotation of the shaft causes the cam to recede from the roll, thus permitting a spring 15 l^6 (the lower end of which bears upon the carriage and the upper end against a collar l^7 secured to the rod l^3) to raise the rod so that the deflector is carried to the opposite position, as shown in dotted lines in Fig. 4 20 and in full lines in Fig. 18.

It will be observed from Figs. 1, 2, and 4, that the frame is provided with hooks or supports n for the reception of the harnesses, indicated at $o o$; and, further, that the warp- 30 threads a^3 pass from the beam a^2 upward and over the cross-bar p and thence downwardly to a comb p' , where they are detachably secured. In operation, where the warp-threads are drawn in manually, the operator 35 passes a suitable implement through the first heddle, through the drop-wire which is in the holder, and engages the first warp-thread, drawing it forward through the drop-wire and through the heddle. Then, 40 the foot-treadle f is depressed, and another drop-wire is released in the magazine and is dropped in position, the threaded drop-wire having been previously transferred from the holder to one of the grooves 45 h^3 . This operation is repeated, again and again, until all of the warp-threads have been drawn through the drop-wires and through the heddles in the two harnesses. The drop-wires are separated alternately 50 into the two grooves of the receptacle h^2 , so that they are ready to be carried therefrom by passing bars through the eyes thereof and deposited in the proper receptacle therefor in the loom, so that they may operate 55 in conjunction with the balance of the stop-motion. Inasmuch as the drop-wires, in passing from the holder to the raceways in the receptacle, are drawn first to the right and then to the left, the warp-threads pass 60 through them, as shown in Figs. 14 and 15, the threads passing through all of the drop-wires in one groove from left to right, and through all of the drop-wires in the other groove from right to left. By this means,

when the threads are drawn taut, after the 65 warp has been exhausted in the loom, the drop-wires may be brought into the same horizontal line, and each alternate drop wire may be easily separated from the adjacent drop wires, so as to arrange said drop wires 70 in angular or crossed relation, as indicated in Fig. 9. It should be understood that the drop-wires are conventionally shown in Figs. 13, 14 and 15 wherein they are illustrated as open or separated so as to be easily seen, 75 but it is plain that the drop-wires can be brought into alinement by loosening the warp-threads m^2 and moving the drop-wires longitudinally of the same into alinement. It is desirable, however, at times to provide 80 for the drop-wires being easily separated or arranged in angular relation, and to this end, I have shown in Figs. 19 to 24, inclusive, drop-wires each of which is provided with a member or projection r on one side with 85 an aperture r' . By placing these drop-wires in the loom initially, with the members r projecting alternately forward and rearward, they may be removed from the loom upon a rod s passed through the eyes thereof, 90 after which rods $s' s'$ may be passed through the apertures r' and the drop wires easily placed in angular relation to each other, as shown in Figs. 23 and 24. It is not essential that the members r should be of 95 any particular shape, it simply being necessary that each alternating drop-wire should be distinguished from the adjacent drop wires, and to secure this end, the thread eyes r^2 may be located a little to one side of 100 the central longitudinal line thereof, so that, in that event, when the rod s must pass through the eyes, the drop wires can be easily moved into the angular relation desired. In such a formation, the member on 105 the drop wire can consist of the slightly larger portion to one side of the eye. Instead of having the member at the upper end of the drop-wire, the member r can be formed on the lower portion thereof, as 110 shown in Fig. 25.

I believe it to be novel to form drop-wires which are alternately distinguishable from those between them, either by broadening one side of the drop wire, or by lengthening 115 the alternating drop wires, and I have contemplated employing these forms in carrying out my invention.

I do not herein claim the structural characteristics alone of the heddles herein 120 disclosed nor of a series of heddles assembled in the relations described except in combination with the mechanical means for operating with or acting upon such heddles. Claims to the said features which are herein 125 unclaimed are embodied in my copending divisional application, Serial No. 824,249, filed March 12, 1914.

Having thus explained the nature of the invention, and described a way of constructing and using the same, although without attempting to set forth all of the forms in which it may be made, or all of the modes of its use, I declare that what I claim is:—

1. The combination with a magazine for holding a plurality of thin drop-wires in a mass and lying flatly one against another with adjacent drop-wires in non-alinement, of a holder for holding said drop-wires flatly against one another in a condition of alinement and means for causing the transfer of the drop-wires one by one from said magazine to said holder.

2. A warp drawing-in machine comprising a magazine adapted for the reception of a pile of drop-wires arranged in angular position with relation to each other, oppositely acting detents for the discharge of a single drop-wire at the bottom of the pile, and means for operating said detents.

3. A warp drawing-in machine having a magazine provided with means for sustaining a plurality of drop-wires arranged in alinement, and means for successively releasing said drop wires.

4. A warp drawing-in machine having a magazine provided with means for receiving and sustaining a pile of drop-wires, each drop-wire being arranged at an angle to the drop-wire immediately above it, and means for successively releasing said drop wires.

5. A warp drawing-in machine having a magazine provided with means for receiving and sustaining a pile of drop-wires, each drop-wire being arranged at an angle to the drop-wire immediately above it, and means for effecting the discharge of the drop-wire at the bottom of the pile without permitting the discharge of the remaining drop-wires.

6. In a machine of the character described, the combination with means for supporting a plurality or mass of drop-wires adapted to lie flatly one against another in a plurality of sets, the members of each set being in alinement and each set being out of alinement with the other set or sets, of means for releasing or discharging said drop-wires one at a time from the remainder.

7. In a machine of the character described, the combination with thin drop wires adapted to lie flatly one above and against another, of means for supporting a pile of such drop wires, and means for releasing the bottom drop wires one by one.

8. In a machine of the character described, the combination with thin drop wires adapted to lie flatly one against another in alinement, said drop-wires having distinguishable features and being arranged so that a drop wire having a different distinguishable feature intervenes between drop wires having similar distinguishable fea-

tures, means for discharging said drop wires one by one, and means for separating said discharged drop wires into independent groups.

9. In a machine of the character described, the combination with means for holding thin drop-wires adapted to lie flatly one against another, said drop-wires having distinguishable features and being arranged so that a drop-wire having a different distinguishable feature intervenes between drop-wires having similar distinguishable features, means for discharging said drop-wires one by one, and means for positioning a discharged drop-wire for a subsequent operation.

10. Means by which a group of drop-wires are arranged and held in alternation, members for discharging independent drop wires therefrom successively, and means for actuating said members.

11. Mechanism for controlling or releasing independent or detached heddles comprising a series of independent heddles characterized by regular, alternate variation of the members of the series; means for holding said series of independent heddles; and releasing or disengaging means adapted to positively reciprocate alternately with relation to the alternate members of said series and release or discharge said members from the series.

12. Mechanism for disengaging or releasing independent heddles from a series of such heddles, which comprises a series of independent heddles characterized by regular, alternate, variation of position of the members of said series; means for holding said series; and releasing or disengaging means adapted to regularly and alternately reciprocate with relation to the alternate members of said series and release or disengage said members from the series.

13. Means for disengaging or releasing independent heddles from a series of such heddles, comprising means for holding a series of independent heddles characterized by regular alternate variation of position of the members of said series, releasing means adapted to act alternately with relation to the members of said series and means for actuating said releasing fingers and causing the successive release or disengagement of the members of said series.

14. The combination with a series of independent heddles characterized by regular, alternate variation in position of the members of the series, of means for holding said series of heddles, and releasing or disengaging means adapted positively to reciprocate alternately with relation to the alternate members of said series, and release or disengage said members from the series.

15. The combination with means for hold-

- ing in compacted mass a series of detached or independent thread-receiving loom elements, of heddle selecting means, said loom elements and selecting means being adapted to present one to the other during the operation of the latter formations, the position of which varies in regular order for successive heddles, whereby the operation of said selecting means causes the release of successive loom elements. 10
16. Mechanism for operating upon independent heddles or the like comprising means to support independent heddles in a series, a heddle releasing key, and means to operate the same to release heddles singly and successively from the series. 15
17. A machine for operating upon a set of independent heddles or the like lying in superposed relation, said machine having heddle turning mechanism to receive a heddle from said set in superposed relation and for turning it to an upright position to locate the eye in alinement with a drawing-in device and means to hold the heddle in that position until a warp thread is drawn through the eye. 20
18. The combination of a magazine in which heddles may lie side by side in a horizontal position; means for releasing heddles in the magazine; and means for causing the released heddles to assume a vertical position for threading. 25
19. The combination of a magazine in which heddles may lie side by side in a horizontal position; means for releasing heddles in the magazine to gravitating movement; and curved guide means for causing the released heddles to assume a vertical position for threading. 30
20. The combination of a magazine in which heddles may lie side by side in a horizontal position, means for releasing heddles in a magazine to gravitating movement, and guide means engaging the ends of the released heddles and shaped so as to cause one end of a released heddle to swing downward in advance of the other end for threading. 35
21. The combination of a heddle magazine, means for supporting a plurality of loom-harness-frames; grooved guides for guiding heddles to pass from the magazine to said frames; and switch means associated with said guides for distributing the heddles to the various frames. 40
22. The combination of a heddle magazine, a plurality of receptacles for heddles, grooved guides for guiding heddles to pass from the magazine to said receptacles, and means associated with said guides for distributing the heddles to the various receptacles. 45
23. In a mechanism for facing heddles for threading, the combination with a magazine for holding a series of heddles in horizontal position, an escapement for causing the release of said heddles one by one and a guide chute wherein said heddle is adapted to gravitate and assume a vertical predetermined position for threading. 50
24. Mechanism for operating upon metallic heddles or the like comprising supporting means whereon said heddles may be suspended, a carriage whereon said supporting means is positioned, and means to support said carriage for traversing movement. 55
25. In a machine for acting upon metallic heddles, the combination with holding means for holding a plurality of such heddles, mechanism for dropping the heddles one by one from the holding means below the level of said holding means for receiving the dropped heddles and positioning them one by one for a threading operation. 60
26. In a machine for acting upon metallic heddles the combination with holding means for holding a plurality of such heddles in a horizontal position, mechanism for dropping the heddles one by one from the holding means and mechanism below the level of the holding means for receiving the dropped heddles and positioning them one by one in a vertical position for a threading operation. 65
27. In a machine for acting upon metallic heddles the combination with means for holding a plurality of such heddles in horizontal position, mechanism for releasing them one by one from the holding means and conveying them to a position at a different level and mechanism for positioning them vertically one by one each at its new level for a threading operation. 70
28. In a machine for acting upon metallic heddles the combination with holding means adapted to hold the heddles in a position of alternate variation, means for releasing them one by one and positioning them for the threading operation and means for placing them in an aligned series after the threading operation. 75
29. In a machine for acting upon metallic heddles, the combination with means for holding a plurality of such heddles in a superposed unthreaded relation, means for withdrawing them one by one from the holding means and positioning them for a threading operation and means for placing them in face to face upright position after the threading operation. 80
30. In a machine for threading metallic heddles the combination with means for holding a series of such heddles unthreaded, means for holding the heddles when threaded in a plurality of series, means for releasing the heddles singly and successively from said first series and conveying the released heddles singly to different threading posi- 85

tions corresponding to the different series of threaded heddles, and means to pass each threaded heddle on to its respective series.

31. In a machine for acting upon metallic heddles the combination with a holder for holding a plurality of such heddles in a non-vertical position, means to release them one by one, means to tip a released heddle to place its longest dimension in a vertical position, means to position a tipped heddle for a subsequent operation and means to partly turn the heddle after the operation from one vertical position to another.

32. In a machine for acting upon metallic heddles the combination with a holder for holding a plurality of such heddles, means to release them one by one, means to tip a released heddle to place its longest dimension at an angle to its initial position and means to position a tipped heddle in its new position for a subsequent operation.

33. In a machine for acting upon metallic heddles, the combination with a holder for holding a plurality of such heddles, means to release them one by one, means to tip a released heddle to place its longest dimension at an angle to its initial position, means to position a tipped heddle in its new position for a subsequent operation and means to partly turn the heddle after said operation about an axis coinciding with its longest dimension.

34. In a machine for acting upon metallic heddles, the combination with means for holding a plurality of such heddles, means to release them one by one, means to convey a released heddle away from the holder and tip the same to place its longest dimension at an angle to its position in the holding means, means to hold a tipped and conveyed heddle in fixed position for a subsequent operation and means to move the heddle on from its fixed position.

35. In a machine for acting upon metallic heddles, heddle holding means, heddle releasing means for releasing them one by one, means to position successively released heddles in alternately different threading positions and means to convey successively threaded heddles to alternate series.

36. In a machine for acting upon metallic heddles, heddle holding means, releasing means, devices for holding successively released heddles in turn in successively different threading positions, means to hold the threaded heddles in a plurality of series equal in number to the number of threading positions and means to convey successively threaded heddles to the respective series each taken in turn.

37. In a machine for acting upon independent heddles or the like the combination with heddle releasing means, of means for holding a series of such heddles to present

to said releasing means a regular alternate variation of position and means to actuate said releasing means to release the heddles singly and successively from the series.

38. In a machine for acting upon independent heddles or the like, the combination with heddle releasing means, of means for holding a series of such heddles to present to said releasing means a regular alternate variation of said heddles and means to actuate said releasing means to release the heddles singly and successively from the series.

39. In a machine for acting upon independent heddles or the like the combination with means for holding a series of such heddles to present each a holding part the position of the holding parts being different for different heddles, releasing means engaging the holding part of the foremost heddle and thereby holding back the series and means to actuate the releasing means to shift the same into engagement with the holding part of the next heddle to release the preceding one.

40. In a machine for acting upon independent heddles or the like, the combination with means for holding a series of such heddles the position of which undergoes a regular alternate variation for successive members of the series and releasing means acting upon the heddles to release and disengage them singly and successively from the series.

41. In a machine for acting upon independent heddles or the like, the combination with heddle releasing means, of means for holding a series of such heddles to present to said releasing means each a holding formation, the holding formation being presented in a varying position for successive heddles of the series.

42. In a machine for acting upon independent heddles or the like, the combination with heddle releasing means, of means for holding a series of such heddles to present to said releasing means each a holding formation, the holding formations being presented in regular alternate variation for successive heddles of the series, and means for actuating the releasing means to release the heddles singly and successively from the series.

43. In a machine for acting upon independent heddles or the like, the combination with heddle releasing means, of means for holding a series of such heddles each to present to said releasing means a holding part uncovered by the next preceding heddle and means to actuate the releasing means to engage in succession the holding parts of the heddles of the series while disengaged from the holding part of each preceding heddle.

44. The combination with means for holding assembled a series of individual detached metallic heddles or the like each com-

- posed of thin resilient sheet material, said elements being held to present holding parts the position of which varies for successive heddles, heddle releasing means engaging 5 the said holding parts and means to actuate the same to release heddles singly from the series.
45. In a machine for operating upon detached warp-thread-engaging elements, in 10 combination, a magazine, a chute and escapement between said magazine and said chute, an operating mechanism and a positioning means below the chute and the operating mechanism.
- 15 46. In a warp drawing machine the combination with heddle holding means, releasing means, a slotted heddle holder for holding a heddle in fixed position to be threaded and means for moving the heddle length- 20 wise the slot after being threaded.
- 25 47. In a machine for acting upon detached heddles the combination with heddle holding means, a chute through which heddles may be conveyed, an escapement be- 30 tween the holding means and the chute, a gate at the outlet end of the chute and positioning means to position a heddle for a threading operation.
- 35 48. In a machine for acting upon de- 30 tached heddles the combination with heddle holding means, a chute through which heddles may be conveyed, an escapement be- 35 tween the holding means and the chute, means at the outlet of the chute to distribute successive conveyed heddles in turn to a plurality of series and positioning means to 40 position a heddle for a subsequent operation after exit from the chute.
49. In a warp-drawing machine the com- 40 bination with holding means for holding de- tached heddles, means for releasing heddles therefrom and a chute through which heddles gravitate from the holding means to 45 a threading position.
50. In a machine for acting upon inde- 50 pendent heddles, the combination with means for positioning the heddles singly for a threading operation, a device for bunching the threaded heddles and means for yield- 55 ingly and reciprocatively actuating it.
51. In a warp-drawing machine, heddle guiding means, a member having a heddle locating slot therein to receive a heddle from 60 said guiding means and means for thread- 55 ing the located heddle.
52. In a warp-drawing machine in com- 60 bination, heddle holding means, releasing means, a chute to convey a released heddle, a member having a slot therein to locate a heddle for the threading operation and means for threading the located heddle.
53. In a warp-drawing machine, in com- 65 bination, a heddle magazine, releasing means, means to guide a released heddle in its movement toward a threading position, a plurality of heddle holders and movable means for directing heddles prior to threading from said guiding means to said holders the latter taken in predetermined order.
54. Means for supporting and successively 70 releasing detached heddles comprising means adapted to engage the sides of a tier of heddles, two escapement devices under-lying and supporting the side portions of the tier and means to actuate the same to 75 cause release of the heddle singly and suc- cessively.
55. The combination with a magazine for holding a series of heddles in horizontal po- 80 sition, of means for releasing heddles from the magazine and causing a released heddle to assume a vertical position.
56. In a machine for acting upon detached heddles, the combination with the heddles holders h^4 , releasing means d^o and $d^{o'}$ for 85 releasing detached heddles, the guide h' in operative relation to said releasing means to receive heddles therefrom, positioning device i' located to receive heddles from said guide, and receptacle h^2 in which the heddles 90 are positioned by said device.
57. In a machine for acting upon metallic heddles, the combination with means to hold a single compact series of such heddles with 95 their flat faces in contact but subject to a regular alternate variation thereby providing two sets in said series, releasing means for each set and means to actuate said re- leasing means in alternation to release 100 heddles singly from said series.
58. In a machine for acting upon metallic heddles, the combination with means to hold a single compact series of such heddles with 105 their flat faces in contact but subject to a regular alternate variation thereby providing two sets in said series, releasing means to release the heddles singly and successively therefrom and means exterior to the heddles for operating said releasing means.
59. The combination with means for hold- 110 ing a series of detached thread-engaging loom elements with successive members dif- ferentially arranged, of means co-operating with the differential arrangement thereof for separating the heddles singly and suc- 115 ccessively from the series.
60. The combination with means for hold- 115 ing a series of flat metallic heddles in an alternately varying arrangement whereby a portion of the flat face of each heddle is un- covered by the preceding heddle, holding means engaging the uncovered portion of a heddle to hold back said heddle and all suc- 120 ceeding heddles and means to actuate the holding means to disengage the same from 125 the first heddle to release the same and to engage the uncovered portion of the next succeeding heddle.

61. In a machine for threading metallic heddles, the combination with means for holding a series of such heddles unthreaded, means for holding the heddles when threaded in a plurality of series, means for releasing the heddles singly and successively from said first series and conveying the released heddles singly to different threading positions corresponding to the different series of threaded heddles, and means to turn a heddle after threading and pass the same on to its respective series.

In testimony whereof I have affixed my signature, in presence of two witnesses.

CHARLES E. BLAIR.
